HIGH PRESSURE SPRAY CLEANING UNIT
FOR VEHICLES OR THE LIKE

Jack Diamond, 6824 Brynurst, Los Angeles, Calif.

Filed Jan. 11, 1965, Ser. No. 83,372

Term of patent 14 years

(Cl. D49—2)

FIG. 1.

FIG. 2.

FIG. 3.

FIG. 4.

FIG. 5.

FIGURE 1 is a perspective view of a high pressure spray cleaning unit for vehicles or the like, showing my new design;

FIGURE 2 is a side elevational view thereof;

FIGURE 3 is a top plan view thereof;

FIGURE 4 is a front elevational view thereof; and,

FIGURE 5 is a side elevational view thereof showing the side opposite to that illustrated in FIGURE 2.

I claim:

The ornamental design for a high pressure spray cleaning unit for vehicles or the like, substantially as shown.
